FIG. 2.

FIG. 3 -

Silvio B. Landa INVENTORS
and Luigi Montevade
ATTORNEY

UNITED STATES PATENT OFFICE.

SILVIO B. LANDÒ AND LUIGI MONTEVERDE, OF GENOA, ITALY.

MOTOR FOR ROTARY MACHINES.

1,169,269.

Specification of Letters Patent.

Patented Jan. 25, 1916.

Application filed December 16, 1912. Serial No. 737,006.

To all whom it may concern:

Be it known that we, SILVIO B. LANDÒ and LUIGI MONTEVERDE, subjects of the King of Italy, residing at Genoa, in the Kingdom of Italy, have invented new and useful Improvements in Motors for Rotary Machines, of which the following is a specification.

This invention relates to rotary motors of the compressed air driven type which are commonly used in boring and drilling machines of the portable variety.

The principal object of the invention is to improve and simplify the general construction of devices of this character.

Another object of the invention is to provide a device of this character wherein the parts will be readily accessible in order that the machine may be taken apart for cleaning or repairs and the several parts quickly re- placed when it is desired to assemble the same.

With the above and other objects in view the invention consists in general of certain novel details of construction and combination of parts hereinafter fully described, illustrated in the accompanying drawings, and specifically claimed.

In the accompanying drawings, like characters of reference indicate the like parts in the several views, and:—Figure 1 is a vertical transverse section through a machine constructed in accordance with this invention. Fig. 2 is a cross section on line II—II of Fig. 1. Fig. 3 is a bottom plan view of the valve casing.

In carrying out this invention there is provided the body 10 which has formed therein a chamber 11 from whence extends a downwardly projecting neck 12. Within the chamber 11 and neck 12 is a bushing 13 forming the lining for the chamber and a bearing in the neck. The rotor 14 of the motor is mounted in the chamber 11 and from each end of this rotor projects a journal 15. The lower journal 15 is fitted within the bushing 13 extending into the neck 12 while the upper journal 15 of said rotor is fitted into a bushing 16 carried in a cover plate 17 securely fixed upon the upper end of the casing and closing the upper end of the chamber 11. Adjacent the chamber 11 the casing is provided with a tubular portion 18 and on the lower end of the casing or bottom of said casing is fitted a bottom piece 19 which has therein an opening 20 alined with the axis of the rotor of the motor. Within

this opening 20 is screwed a foot step bearing 21 so arranged that an extension 22 upon the journal of the motor which projects downwardly through the neck 12 can rest thereon and thus prevent longitudinal movement of said rotor.

Within the tubular portion 18 is mounted a bushing 23 and alined with the tubular portion 18 is a tubular portion 24 formed on the bottom plate and also provided with a bushing 25. Slidably and rotatably mounted in the bushings 23 and 25 is a tool socket 26 of the usual form. At 27 is indicated a feed screw sleeve and this feed screw sleeve has a lower end 28 which passes through a suitable opening in the cover plate 17 and is screwed into the tubular portion 18. Between the feed screw sleeve and the bushing 23 are mounted the anti-friction washers 29 which are kept separate by means of the ball bearings 30. Screwed into the sleeve 27 is a hollow feed screw 31 having a closed upper end. This closed upper end is indicated at 32 and it is provided with an upwardly extending center point 33 to enable it to be held beneath the upper arm of what is commonly called "old man". Extending into the hollow portion of the feed screw is a stem 34 the lower end of which extends into the socket 35 provided in the tool socket 26. Fixed on the solid end 32 is an operating handle 36 and when this handle is rotated it carries with it the feed screw and consequently causes movement of said screw along the sleeve 27 so that the stem 34 is carried down or allowed to move up according to the direction of the revolution of the feed screw and thereby forced the tool, carried in the socket 26, into the work or permits its removal from the work. Extending laterally from the casing 10 is a tubular member 37 wherein is screwed a handle 38 so that the device properly handled in transporting it from place to place and in placing it in position for work.

Between the portions 15 and 22 of the motor extension is provided a shaft 39 whereon is mounted a pinion 40. This pinion 40 meshes with a gear 41 splined to the sleeve 26 so that while the gear causes the sleeve to revolve yet the sleeve can move longitudinally through the gear, the latter being held in position between the two tubular portions 18 and 24.

The motor 14 is of the reversible type but it is not deemed necessary here to show any of

the particular mechanism involved in the motor other than the reversing valve. This reversing valve is held in a tubular extension 42 arranged opposite the tubular member 37 and includes a valve casing 43 of frusto-conical form and having ribs 44 formed thereon to hold the valve casing in proper spaced relation and to provide inlet and outlet ports 43' and 44' communicating with the motor. This casing is furthermore provided with a port 45 which communicates with a nipple 46 extending through the tubular portion 42 so that an air hose may be attached thereto for a supply of the compressed air. Within this valve casing is mounted a frusto-conical plug valve 47 having a partition 48 extending thereacross and on one side of the partition are provided the ports 49 while on the other side of the partition are provided similar ports 50. On the last mentioned side of the partition 48 there is also provided an exhaust port 51 which extends through the hub 52 of said valve and leads 25 into a sleeve 53 which is held in position in a bushing 54 by a second bushing 55 as clearly shown in Fig. 1. This sleeve is provided with a knurled handle 56 and has at the end of it a tap 57 having a series of 30 small perforations 58 formed therein so that the cap constitutes a muffler. Within the sleeve is formed a diaphragm 59 having an opening 60 in the center thereof and between this diaphragm and the valve is held 35 a coiled spring 61 which normally holds the valve close in the casing 43. Now it will be obvious that by rotating the valve from the position shown in Fig. 2 through one-quarter of a circle the port 43' will be cut out of 40 communication with nipple and the port 44' cut in. At the same time the port 44' will be placed in communication with the opposite side of the partition 48 and thus the port 43' becomes the exhaust port where 45 formerly it was the intake port. It will also be obvious that upon removal of the sleeve 27 the cover plate 17 can be readily

taken off and access had to the motor and all the parts connected therewith. In like manner upon removal of the nipple 46 and sleeve 54 the entire valve mechanism can readily be withdrawn for inspection or repairs. Furthermore upon removing the bottom plate 19 the lower part of the device is accessible. Thus any part of the device 55 can be readily reached for the purpose of replacement or repair.

There has thus been provided a simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed.

Having thus described the invention, what is claimed as new, is:

In a motor of the character described, a casting having a tubular extension, a valve casing mounted in said extension and provided with ribs to form inlet and exhaust passages between the casing and extension, said extension having a supply opening and said casing having a similar supply opening registering therewith, said casing further having ports communicating with said passages, a hollow plug valve revolvably mounted in said casing and provided with a diametrically disposed partition arranged to divide the valve into two chambers, said valve further having a pair of ports leading from each chamber and arranged to bring either of the ports in the casing into communication with the supply opening, and said valve further having a third port constituting an exhaust port leading from one of said chambers, and means for rotating said valve.

In testimony whereof we affix our signatures.

SILVIO B. LANDÒ.
LUIGI MONTEVERDE.
